UNITED STATES PATENT OFFICE.

GUSTAV PISTOR, HERMANN LANG, AND ROBERT SUCHY, OF BITTERFELD, GERMANY,
ASSIGNORS TO THE FIRM I. G. FARBENINDUSTRIE AKTIENGESELLSCHAFT, OF
FRANKFORT-ON-THE-MAIN, GERMANY.

PRODUCTION OF PHOSPHORUS PENTOXIDE AND PHOSPHORIC ACID.

Application filed October 11, 1926, Serial No. 141,025, and in Germany October 22, 1925.

In the manufacture of phosphorus pentoxide and phosphoric acid by combustion of yellow phosphorus the phosphorus was heretofore generally melted in vessels and a current 5 of air was conducted over its surface. Now we have found that this method is not practicable when large quantities of phosphorus are to be burnt. This is, on the one hand, due to the fact that phosphorus, owing to its great 10 combustion heat, is heated to a high temperature and is evaporated so rapidly that the available quantity of air does not suffice to attain a complete combustion; on the other hand the surface of the phosphorus is coated 15 with lower oxidation products and also with phosphoric acid, if the combustion air is moist, whereby a uniform combustion is prevented.

It has already been proposed to burn phosphorus with the aid of a wick (German patent specification No. 110,174), but even this method cannot be carried out on a large scale with ample efficiency and certainty.

In contradistinction to what is known we 25 have found that any desired quantity of phosphorus can be burnt without difficulty by employing nozzles to which molten phosphorus is supplied in the form of a "liquid combustible". Preferably burners provided with nozzles of the type used for oil-burners are employed. The molten phosphorus may be supplied to the nozzle from an elevated vessel by its own hydrostatic pressure or by any pumping device.

An apparatus for carrying out our improved method is diagrammatically illustrated in the annexed drawing, of which Fig. 1 is a sectional view of the burner and Fig. 2 is a sectional view of the whole plant.

The burner *a* comprises an inner tube *b* end-

ing in a nozzle *c* through which the liquid phosphorus is fed. The tube *b* is surrounded by a wider tube *d* the lower end of which is contracted to form an annular slot *e* around the nozzle *c*. The combustion air is introduced through a tubule *f* and ejected through slot *e*. This construction of a burner is old in the art of oil-heating and forms no part of our invention.

g in Fig. 2 is the container for liquid phosphorus from which the feeding pipe *b* issues. The burner *a* is inserted into the top wall *h* of the combustion chamber *i* consisting of an upper cylindrical and a lower conical part *k* and *l* respectively. The combustion chamber *i* communicates through a pipe *m* with a collector *n* having the same form as the combustion chamber and provided near the top with a pipe *o* for carrying away the waste gases. The phosphorus pentoxide is withdrawn by valves *p* and *p'* and may be collected in a lorry *q*.

The combustion chamber *i* may be cooled by water flowing in the form of a thin film out of an annular reservoir *r*, open at the bottom, and collecting in an annular reservoir *s* provided with an outlet *t*.

We claim:—

The method of producing phosphorus pentoxide and phosphoric acid by the combustion of yellow phosphorus, comprising passing molten phosphorus through nozzles and burning the jets of phosphorus thus produced.

In testimony whereof we affix our signatures.

GUSTAV PISTOR.
ROBERT SUCHY.
HERMANN LANG.
